US00D408377S

United States Patent [19]

Ferchau et al.

[11] Patent Number: Des. 408,377

[45] Date of Patent: **Apr. 20, 1999

[54] **PORTABLE DEVICE FOR
COMMUNICATING WITH MAGNETIC
STRIPE AND INTEGRATED CIRCUIT
CARDS**

[75] Inventors: **Joerg U. Ferchau; Kenneth A. Kotyuk, both of Morgan Hill; Benjamin Sherman, Milpitas, all of Calif.**

[73] Assignee: **Tandem Computers Incorporated, Cupertino, Calif.**

[**] Term: **14 Years**

[21] Appl. No.: **29/086,854**

[22] Filed: **Apr. 20, 1998**

[51] LOC (6) Cl. **14-02**

[52] U.S. Cl. **D14/105**

[58] Field of Search **D14/100, 105, D14/107, 118; 250/556; 235/454, 462, 470, 380, 382.5, 382, 472, 476, 482, 483; 355/81**

[57] **CLAIM**

The ornamental design for a portable device for communicating with magnetic stripe and integrated circuit cards, as shown and described.

DESCRIPTION

FIG. 1 is a top front and side perspective view of the portable device for communicating with magnetic stripe and integrated circuit cards showing our new design;

FIG. 2 is a bottom rear and opposite side view thereof;

FIG. 3 is a rear view thereof;

FIG. 4 is a bottom plan view thereof.

The broken lines are shown in the views for illustrative purposes only and form no part of the claimed design.
